TENSIONING DEVICE FOR YARN THROWING
MACHINES OF THE UP-TWISTER TYPE

Herbert Lasch, Withington, Manchester, England

Application October 16, 1943, Serial No. 506,496
In Great Britain October 16, 1942

5 Claims. (Cl. 57—106)

This invention relates to the tensioning devices of yarn throwing machines of the up-twister type, in which a yarn (for example a continuous filament yarn) is led endwise from a vertically-disposed bobbin by a flyer rotatable on the axis of the bobbin, then upwards through a balloon guide, further upwards to a glass or like guide rod, and from thence through a suitable traverse guide to a cheese or equivalent receiver.

In practice, the balloon guide requires to be accurately spaced with respect to the upper end of the bobbin and to the flyer above the bobbin, in order to impart just the correct length and tension to the balloon. However, since the diameter of the wound bobbin varies as the yarn is drawn off, the tension in the balloon, and consequently in the yarn above the balloon is varied. Also, as the point of unwinding of the yarn moves from the top to the bottom of the bobbin, there is a consequent variation of the tension in the yarn. This has meant that, for a given machine, with a given spindle speed and gauge of flyer, and with a given type of yarn, the maximum and minimum diameters of the wound bobbins, the number of turns on the bobbin for each traverse of the guide and the spindle speeds have been restricted, since for any given position of the balloon guide the maximum spindle speed, and the range of efficiency amongst the several variables is fixed.

In the event of the tension becoming too small, the twist will be imparted to the yarn unevenly, which will cause snarls and consequent weakness, and these snarls may pass on to the cheese, impair the quality of the twisted yarn, and give trouble in later operations. On the other hand, in the event of the tension becoming too great, it may result in over-stretching of the yarn, also with consequent weakness, even if actual breakage does not occur. Although these two extremes may be avoided by proper choice and setting of the above-mentioned variables, the variation of the tension due to the difference of the diameters of the package on the bobbin during the process, and due to the traverse length of the bobbin still remain, and cause unevenness in the twist imparted to the yarn, with consequent variation in the tensile strength, this defect being particularly obvious with the coarser counts. This unevenness results also in a varying shrinkage factor and a varying affinity to dyestuffs in the ultimate woven or knitted fabrics in the finishing processes, since during the wet treatments, the differently-tensioned por-

tions of the yarn seek to recover their respective original molecular conditions. With a fixed balloon guide, the supply package or bobbin has to be wound very accurately and fairly hard, and during such winding operation the yarn must be kept under considerable tension, which again may cause stretching. Any soft layers, loose yarn ends, or protruding filaments, may tend to catch the balloon during the throwing operation and increase the tension dangerously to the breaking point. For the above reasons, yarns containing filaments of certain staples have not hitherto been processed successfully on machines of the up-twisting type.

15 The new tensioning device according to this invention aims at overcoming all these difficulties automatically, by arranging for variations in the tension in the yarn to be automatically corrected, and in such a manner that not only the increased tension in the yarn which has gone forward, and in which the increase originated, is relieved, but also any increased tension in the balloon is reduced to normal so as not to affect the on-coming yarn.

20 25 The accuracy of the winding of the supply bobbin is therefore no longer of such importance, and the use of this invention will permit also of the throwing of staple fibre yarns in an up-twister machine. Further, the receiver cheese or bobbin will, because of this invention, be wound with an even tension throughout the twisting operation, resulting in a perfectly-wound package.

The main advantages therefore are, evenly imparted twist resulting in a high average of tensile strength due to the even tensioning of the yarn, as well as a greater range of the above-mentioned variables, of which the most important one is the possibility of using larger supply packages. The improved tensioning device can also be used successfully for any type of overend winding where the control of the balloon area is essential for maintaining evenness of tension during the winding process.

45 According to this invention, in the throwing of yarns on an up-twister throwing machine, the yarn coming from the supply package and flyer is caused to pass through two movable guides arranged to give it a substantial deflection, and one of which functions as a balloon guide; the position of the guides (and therefore the amount of deflection) being determined by the tension of the yarn against the influence of counter-weight means; and so that any increase of tension moves one guide towards the straightened-out position of the yarn so as to diminish the angle of deflec-

tion and in so doing relieves the tension in the foregoing yarn, whilst at the same time lowering the balloon guide to shorten the balloon and thus relieve the tension in the oncoming yarn. Any reduction of tension causes or allows the guides to move in the opposite direction with the opposite result.

In a typical apparatus for carrying out the invention the usual fixed balloon guide is dispensed with, and in its place is a pivotally-mounted balloon guide, whilst a further pivotally-mounted guide substantially deflects the yarn between such balloon guide and the aforesaid glass rod, both the guides being overbalanced by a common counterweight, but being capable of yielding under any increased tension of the yarn; the latter to lessen the degree of deflection in the yarn and thus allow a short extra length to go forward to relieve the increased tension in the foregoing yarn, where it originated, and the former to reduce the tension again, back to normal, by moving towards the bobbin.

According to a further feature of the invention, the counterweight is so mounted that between its possible extreme positions it passes through a position of maximum effect. By this arrangement the total tensioning effect of the guides on the yarn cannot exceed a pre-determined amount, and moreover, begins to fall again as the balloon guide approaches its lowest position, nearest the flyer.

In the accompanying drawings one example of the invention is illustrated:

Fig. 1 is a side elevation of the device (with its support in cross section), the "minimum-tension" position of the device being shown in full lines, with certain portions shown in a "greater-tension" position in broken lines;

Fig. 2 is a similar view to Fig. 1, but with full lines showing the parts in a "greater-tension" position, and certain portions shown in the "minimum-tension" position in broken lines; and

Fig. 3 is a plan.

In the drawings, there is a carrier member 1, made for example of a zinc alloy diecasting, and comprising a shorter forwardly-extending portion 2 and a longer rearwardly-extending portion 3. The forwardly-extending portion 2 forms the upper jaw of a clamp, and has on its top side a vertically-extending member 4, serving as a temporary holder to receive the flyer and the spindle button when they are removed from the spindle, say for the changing of a bobbin. The rearwardly-extending portion 3 is inclined downwardly at an angle to the forwardly-extending portion 2, and is formed at its lower end with a lateral extension or boss 5, having a hole 6 which forms a pivot for one of the guides as hereinafter mentioned.

This carrier member 1 is secured to one of the usual transverse bars *x* of the machine, by means of the forwardly-extending portion 2 and an attached member 6 which forms the lower jaw of the clamp, the two jaws being connected together by the pivot pin 7, and being clamped on to the rod *x* by the screw and nut 8. Tightening of the screw 8 causes the jaws to bind on the pin 7 and hold it, but split pins 9 are passed through it as an additional safeguard against endwise movement. Also mounted on the pin 7 is a member 10 described below.

The movable guide (i. e. the balloon guide) 11 is of stainless steel wire and is pivotally mounted by its rear end in the lateral extremity or boss 5 of the rearwardly-extending part 3 of the car-

rier member, and at its forward end is bent first upwardly at 12, then rearwardly at 13 and laterally at 14, and this last portion is formed with a pig-tail loop 15.

- 5 Pivotedly mounted on the pin 7 is the member 10 which is a bifurcated bracket having a short lateral bush 10a on the side nearest the carrier member, and below which passes the wire 11 of the balloon guide. This bracket carries the other 10 yarn guide 16 extending upwardly behind the said transverse bar *x* of the machine, and then laterally (see Fig. 3) having a wide pigtail loop 17 at its upper end of which the centre is in line with the pigtail 15 of the balloon guide. Fixed 15 to the same bracket 10 is a further wire 18 which extends forwardly and at its front end has a wide lateral loop 19 serving as a support for the long wire 11 of the balloon guide. This wire 18 also extends rearwardly from the bracket 10, being 20 bent downwards at an angle to its forward part, and the lower end carries a counterweight 20 which also is bifurcated and clips on to the wire 18, being adjustable along such wire, thus determining the effectual amount of counterweight. 25 The weight is held in the adjusted position by the screw 21. The bracket 10 has two parallel openings across the central gap, to locate respectively the wire 18 and the lower end of the fixed guide 16, which latter is curled around the 30 wire 18.

In use, with the parts in the position shown in full lines in Fig. 1, the lower yarn guide 11 has its pig-tail loop 15 a certain distance above the position which would be occupied by the usual 35 fixed balloon guide, whilst the pig-tail loop 17 of the other yarn guide is behind the plane of the said transverse bar *x* of the machine, so that there is a substantial deflection in the yarn between the lower guide and the usual glass guide 40 rod (not shown) at the upper part of the machine.

The counterweight 20 should be adjusted in such a way that it gives at its maximum effect (i. e. slightly above the horizontal position of wire 45 18) the required predetermined tension to the thread.

Should the tension in the yarn increase, for any reason, the upwardly-extending guide 16 will 50 be pulled forward and thereby partly straighten out the deflection in the yarn, and also, by displacing the support 19 at the forward end of wire 18 (owing to rotation of bracket 10 on pin 7) causes the balloon guide 15 to move downward by its own weight. Since the length of yarn between 55 the balloon guide 15 and the glass rod in this straightened-out position is less than that length when the guides are in original position, the difference represents a temporary extra supply to the receiver package which will be sufficient to 60 relieve the tension in the yarn which passed forward immediately before the change took place, whilst the downwardly moving balloon guide 15 will, to some extent, shorten the balloon area, and bring the tension in the on-coming yarn back to 65 normal.

The actual form of each of the guides, and of 70 their respective supports, of the counter-weight means (which may be a spring) and of the means for mounting the device to the machine, may vary, so long as the function of the device, as above defined, is not interfered with. There will be no possibility of the yarn cutting in on the pigtails, because in the lower pigtail the thread 75 will balloon around and not run continually on

one spot, whilst in the upper guide the thread will traverse from side to side.

What I claim is:

1. A yarn-tensioning device for a yarn throwing machine comprising a pivotally-mounted balloon guide mounted so that its to-and-fro pivotal movements shorten and lengthen the balloon, a further pivotally-mounted guide moving in a path substantially at right angles to the path of the balloon guide, and a single counterbalance means for the two guides tending to maintain them in relative positions which substantially deflect the yarn, the movements of the further guide being such as to lessen the deflection of the yarn as the balloon guide shortens the balloon and to increase the deflection of the yarn as the balloon guide lengthens the balloon.

2. A yarn-tensioning device for a yarn throwing machine comprising a carrier member adapted to be fixedly held to a fixed part of the machine, a balloon guide pivotally mounted in the carrier member, a bracket pivotally supported on the carrier member, means on such bracket forming a support for the balloon guide, counterweight means carried by the bracket and a further yarn guide carried by the pivoted bracket, the two guides being moved simultaneously by the counterweight to positions where they substantially deflect the yarn, passing through them, and being moved against the counterweight to positions where they lessen the deflection of the yarn, and simultaneously shorten the balloon.

3. A yarn-tensioning device for a yarn throwing machine comprising a carrier member having at its forward end one jaw of a clamp and extending rearwardly therefrom, a further clamp jaw pivotally connected to the carrier member and, with the first jaw, adapted to grip a fixed part of the machine, a balloon guide pivotally mounted in the rear-end of the carrier member and extending forwardly thereof so as to rise and fall to lengthen and shorten the balloon, a bifurcated bracket pivotally mounted on one side of the carrier member, a yarn guide held in the bracket

and extending upwardly therefrom and a supporting member also held in the bracket, extending forwardly to support the balloon guide, and extending rearwardly, and a counterweight adjustable on the rearward extension of the supporting member tending to return both guides to positions where they increase the deflection of the yarn as the balloon is lengthened.

4. In a yarn-tensioning device for a yarn throwing machine, a yarn guide, a counterweight and a support for a balloon guide, all connected together for simultaneous pivotal movement, a carrier member pivotally carrying the said parts, and a balloon guide resting on said support, the balloon guide being pivotally mounted in the said carrier member and arranged so that as it moves down to shorten the balloon the two guides approach positions which lessen the deflection of the yarn, and as it moves upwards to lengthen the balloon the two guides approach positions which increase the deflection of the yarn.

5. A yarn-tensioning device for a yarn throwing machine comprising a two-part carrier member having its two parts shaped and pivotally connected together as complementary jaws, a laterally-extending pivot pin for those jaws, a bifurcated bracket pivotally mounted on such pin and having a laterally-extending boss around the pivot on the side nearest the jaws, upper and lower cavities in the bracket, a yarn guide held in one cavity, and a supporting member held in the other cavity, such supporting member extending rearwardly and forwardly of the bracket, an adjustable counterweight on the supporting member, and a balloon guide pivotally mounted in the carrier member, passing beneath the said laterally-extending boss, and resting on the supporting member, and movement of the guides against the counterweight lessening their deflection of the yarn, whilst reverse movement due to the counterweight increases the deflection of the yarn.

HERBERT LASCH.
